UNITED STATES PATENT OFFICE.

THOMAS JEFFERSON EUBANKS, OF ROGERS, TEXAS, ASSIGNOR OF ONE-HALF TO F. M. CHANDLER, OF SAME PLACE.

CULTIVATOR.

SPECIFICATION forming part of Letters Patent No. 339,632, dated April 13, 1886.

Application filed February 3, 1886. Serial No. 190,695. (No mod'l.)

To all whom it may concern:

Be it known that I, THOMAS JEFFERSON EUBANKS, a citizen of the United States, residing at Rogers, in the county of Bell and State 5 of Texas, have invented a new and useful Improvement in Cultivators, of which the following is a specification, reference being had to the accompanying drawings.

My invention relates to an improvement in 10 cultivators; and it consists in the peculiar construction and combination of devices, that will be more fully set forth hereinafter, and particularly pointed out in the claims.

The object of my invention is to provide a 15 device to enable the shovels of the cultivator to yield when they strike an immovable object—such as a stone or stump—and thereby prevent the cultivator - shovels from being broken, and more especially in time-saving in 20 readjusting the shovel for plowing.

In the drawings, Figure 1 is a side elevation of a cultivator embodying my invention. Fig. 2 is a top plan view of the same. Fig. 3 is a vertical transverse sectional view, taken on 25 the line *xx* of Fig. 2. Fig. 4 is a detail transverse sectional view.

I have herein shown my invention as applied to a single shovel cultivator for convenience in illustration; but it will be readily understood that my improved devices are adapted 30 to be applied to cultivators having two or more shovels or plows, and which are adapted to be drawn by one or more horses.

A represents the cultivator-beam, and B 35 represents a metallic clip having depending flanges C, which bear on opposite sides of the upper portion of the rear end of the beam. This clip has a longitudinal slot, D, made in its front end on its upper side, and from one 40 side of the clip, at the upper edge thereof, extends a lateral flange or plate, E; in the front edge of which is made a V-shaped opening, F.

G represents a lower clip or casting which is provided with flanges H, to engage the sides 45 of the beam A below the clip B, and has a depending standard, I, in the lower end of which is made an opening, K.

L represents a metallic block, which has a transverse groove, M, on its outer side, and 50 through this block passes a pivotal bolt, N, the outer end of which is bent in a semicircle

to form a keeper to secure the plow-foot O in the groove M on the block. The shank of the bolt passes through the opening K in the lower end of the standard I, and on the inner side 55 of the said standard washers and nuts P are secured on the threaded shank of the bolt, to clamp the block L and the plow-foot to the standard. The upper end of the plow-foot rests normally in the V-shaped opening F of 60 the clip B.

The clips B and G are secured to the beam by a bolt, R, which passes down through the slot D and through a vertical opening in the beam, and through the lower side of the clip 65 G. A nut, R', is screwed on the lower projecting end of the bolt R, and thereby clamps the clips B and G firmly to the beam A. By reason of the slot D it will be seen that the clip B may be moved forwardly or rearwardly 70 on the beam; but the clip G is immovable. As the plow - foot is pivoted to the depending standard of the clip G, and as the upper end of the said foot rests in the inner end of the opening F in the clip B, it follows that by moving 75 the said clip B the angle of the plow-foot may be adjusted to any requisite degree to cause the shovel or plow to run in the ground at any desired angle. As the upper end of the plow - foot bears against the converging 80 sides of the opening F it is held rigidly therein and prevented from playing laterally.

S represents a pair of pivoted jaws, which are fulcrumed together and are pivoted to the plate E in rear of the opening F by means of 85 a bolt, T. The front ends of the jaws S are cut obliquely in opposite directions, as at S', and at the inner ends of the oblique edges S' is formed a semicircular opening, S'', for the reception of the upper end of the plow foot, 90 one-half of the said opening being formed in each jaw.

S' represents rearward-diverging arms with which the fulcrumed jaws are provided, and the said arms are connected by a bolt, T', that 95 passes through slotted openings made in the rear ends of the arms. A coiled extensile spring, U, is placed on the bolt T', and bears between the arms S', and on the outer end of the bolt T' is a nut, T'', by means of which the 100 tension of the spring may be regulated, and whereby the jaws S may be partly opened, so

as to permit the upper end of the plow-foot to readily disengage itself therefrom. The outward movement of the arms S³ is limited by stops E', which are made on the rear side of

5

the plate E.

When the cultivator or plow is in operation the tension of the springs on the clamping-jaws is sufficient to hold the plow-foot against the resistance of the soil as the shovel runs there-
10 through. When the shovel strikes a stone, stump, or other obstruction, the upper end of the plow-foot is freed from the clamping-jaws and the shovel is turned on its pivotal bolt to the position shown in dotted lines in Fig. 1,
15 and passes unharmed over the stone or ob-
struction. The plowman with his foot presses against the lower end of the shovel-foot and throws the upper end thereof rearwardly into re-engagement with the clamping-jaws with-
20 out further loss of time.

Having thus described my invention, I claim—

1. The combination, in a plow or cultivator, of the pivoted plow-foot, the clamping-jaws
25 for engaging the upper end thereof, the said jaws having the oblique opposite inclined

front ends, S', and the opening S², made in their opposing sides at the inner ends of the said oblique edges to receive the plow-foot, sub-
stantially as described.

2. The combination, in a plow or cultivator, of the pivoted plow-foot, the clip B, secured on the plow-beam and movable longitudinally thereon, the said clip having the extending plate E, provided with the opening F, and the spring-actuated clamping-jaws for securing the upper end of the plow-foot, substan-
35 tially as described.

3. The combination of the beam, the clip G, firmly attached thereto, the plow-foot piv-
40 oted to an arm depending from clip G, and the clip B, movable longitudinally on the beam and provided with devices for engaging and locking the upper end of the pivoted plow-
foot, substantially as described.

In testimony that I claim the foregoing as my own I have hereto affixed my signature in presence of two witnesses.

THOMAS JEFFERSON EUBANKS.
